(57) **CLAIM**

The ornamental design for a scooter with rear support as shown and described.

DESCRIPTION

FIG. 1 is an isometric view of a scooter with rear support showing my new design having a wheelchair attached thereto;

FIG. 2 is a front elevational view thereof;

FIG. 3 is a top plan view thereof;

FIG. 4 is a bottom plan view thereof;

FIG. 5 is a right elevational view thereof; the left side elevational view is a mirror image of the right elevational view thereof; and,

FIG. 6 is a rear elevational view thereof showing my design. The broken line showing of a wheelchair and tablet is included for the purpose of illustrating portions of the "article" and forms no part of the claimed design.
